CATALYTIC CONVERSION OF HIGHER-
BOILING HYDROCARBONS INTO
LOWER-BOILING HYDROCARBONSEugene J. Houdry, Paris, France, assignor to
Houdry Process Corporation, Dover, Del., a
corporation of Delaware

Application May 11, 1932, Serial No. 610,567

11 Claims. (Cl. 196—52)

This invention relates to improvements in processes of and apparatus for the conversion of higher boiling hydrocarbons into lower boiling hydrocarbons by contact with an active mass at an elevated temperature and the subsequent refining in contact with another active mass at elevated temperature with the subsequent regeneration or reactivation of these respective active masses in situ.

One object of the invention is to devise improved ways and means for producing a motor fuel suitable for use in high compression internal combustion engines which is characterized by a high yield of the lower boiling hydrocarbons from higher boiling hydrocarbons, by stability against undesirable oxidation, which often results in the production of objectionable products either in storage or in use, and by high antiknock value.

The advantages of catalytic conversion of higher boiling hydrocarbons into lower boiling hydrocarbons in accordance with the present invention are indicated by a comparison with conventional thermal decomposition or pyrolytic cracking methods by which products having substantially the same antiknock characteristics are secured. Thermal decomposition of high boiling hydrocarbons causes a non-selective acceleration of reactions at high temperatures with excessive losses due to high gas yields. The product which results is refined only with difficulty and even then the resulting product is inferior as far as stability against undesirable oxidation is concerned. Catalytic conversion by the present invention effects a selective acceleration of certain desirable reactions with losses which are not excessive, i. e. with low gas yields. The product requires no further refining and has very high stability against undesirable oxidation. In addition, a much higher antiknock rating can be obtained from the same charging stock than is possible with the conventional pyrolytic methods.

The single figure is a diagrammatic disclosure of one form of apparatus for practising the invention.

Referring to the drawing, the charge of material to be converted, such as gas oil, preferably in a partially heated state, is admitted through valved line 2 and passed with or without admixture of vapor such as steam from valved line 4 into line 6 and thence into pipe still 8. The vapors and atomized portion of the charge preferably pass from still 8 through vapor line 10 into a separator 12 where the atomized portion

is extracted from the vapor and passes as liquid through valved line 14 through heat exchanger 16 through valved line 18 into vented storage tank 20. The vapors pass through line 22 into one of the two valved lines 24 or 26 leading to insulated catalyst chambers 28 and 30 respectively which contain suitable catalytic material for effecting the desired conversion. The resulting products, still in vapor phase, issue either through valved line 36 or 38 into vapor line 40 which includes heat exchangers 42 and 46 and discharges into fractionating column 50 where separation is effected between lower boiling vapors and higher boiling liquid. The higher boiling liquid is withdrawn through valved line 52, heat exchanger 54 and valved line 56 into vented storage tank 58. The fractionation desired in the column is partially or wholly controlled by directing some or all of the charge through closed heat transfer system 60 or by circulating a cooling medium through closed coil 62 located in the top of the column or by both such means. The vapors of the lower boiling hydrocarbons pass through vapor line 64, heat exchanger 42, vapor line 66 into one of the two valved lines 68 or 70 which discharges into catalyst chambers 72 and 74 respectively which contain suitable catalytic material for refining and stabilizing the hydrocarbon vapors. The latter pass after treatment by valved line 80 or 82 respectively into vapor line 84 which discharges into a second fractionating column 86 where separation again takes place, into lower boiling vapors and higher boiling liquid. The higher boiling liquid is withdrawn through valved line 88, heat exchanger 90 and valved line 92 into vented storage tank 94. The fractionation in column 86 is controlled by means of a distributor 96 in the top of the column to which a portion of the condensate of the finished product is returned. The uncondensed vapors from the column pass through vapor line 98 into condenser 100 and thence by line 102 into gas separator 104. The gas is withdrawn through valved line 106 and the liquid condensate passes through line 108 into vented storage tank 110. Condensate is withdrawn as needed through valved line 112 and is forced by pump 114 through valved line 116 into distributor 96.

The fresh feed or charge in storage tank 118 passes through valved line 120 and is discharged under pressure by pump 122 into valved line 124 through heat exchanger 90, line 126, heat transfer system 60, line 128, valved line 130, heat exchanger 54, line 132, heat exchanger 46, valved

line 134, heat exchanger 16 into valved line 2. The control of heat transfer for proper operation of the system is maintained by the use of valved lines 136, 138, and 140 as required. The charge may also be discharged from pump 122 in whole or in part through valved line 136 into valved line 2. After the fresh feed in storage tank 118 is exhausted, additional runs on reflux material may be made by connecting tanks 94 and 58 together or in succession to pump 122, until the ultimate yield of the original charging stock is attained.

The catalytic chambers 28, 30 and 72, 74 are provided in pairs in order that the plant may be in continuous operation, one chamber of each pair being on stream, while the other is in regeneration, and each chamber alternating in function. The catalyst used in chambers 28 and 30 may be of any known type which will effect the desired conversion of high boiling hydrocarbons into low boiling hydrocarbons, but must be in a form which will permit regeneration in situ. Thus fragments of metals having selective adsorptive or catalytic activity may be used, such as iron, nickel, cobalt or molybdenum, or oxides of such metals, especially when supported on a suitable carrier, or fuller's earth or activated hydrosilicate of alumina in molded form, especially of restricted ferric oxide content (not more than 3%) as disclosed in my copending application Serial No. 600,581, filed March 23, 1932. Catalytic material having the necessary selective adsorptive properties to remove gum-forming constituents from the transformed vapors and to stabilize the same may be taken from the above list for refining chambers 72, 74, but by preference it comprises activated hydrosilicate of alumina of the composition described in my aforesaid copending application having admixed therewith a suitable metallic oxide, such as nickel oxide, and the mixture molded into rigid pieces of suitable size and shape. By preference, regeneration of the catalytic mass in each of the aforesaid chambers is effected in situ by first admitting steam and then air with steam or with other inert material, such as flue gas, in order to control the temperature of regeneration, as disclosed in my copending application Serial No. 604,997, filed April 13, 1932. The regenerating medium may be admitted to catalytic cases 28 and 30 by valve inlets 138 and 140 and the fumes may be vented therefrom through valve outlets 142 and 144 respectively. Similarly a regenerative medium to be followed later by a reducing gas may be supplied to the refining chambers 72, 74 by valved inlets 146 and 148, respectively, and the fumes may be vented therefrom by valved outlets 150 and 152, respectively.

The operation of the apparatus for the conversion of higher boiling hydrocarbons into lower boiling hydrocarbons may be further described by giving the details of typical runs with two different charging stocks, including the approximate operating temperatures and pressures. A fresh Coastal gas oil charging stock with a distillation range from 400 to 700° F. and a gravity of 40° A. P. I. was fed to pipe still 8 whose outlet temperature was maintained at about 850° F. Any unvaporized portion of the oil was segregated in tank 20. The vapors passed at about 845° F. into one of the two conversion chambers 28, 30 in contact with the catalyst therein which was maintained at a temperature of about 835° F. and under a gauge pressure less than 15 lbs. per sq. in. The pressure was merely for the purpose of forc-

ing the vapors through the system. The vapors were cooled by passing through heat exchanger 42 and 46 and discharged into fractionating column 50 where they were separated into lower boiling hydrocarbons of approximately motor fuel distillation range and into higher boiling hydrocarbons which were collected as liquid in tank 58 and were subsequently used as a charging stock for another run. The fractionation in the column was controlled by the use of partially heated charging stock in line 60 and by cooling coil 62 in the top of the column. The vapor issuing from the top of the column at about 335° was stepped up to about 650° F. in heat exchanger 42 and then passed into one of the two refining and stabilizing chambers 72, 74 where the temperature was maintained at about 650° F. The refined and stabilized vapors were then conducted to the second fractionating column 86 where final separation of the hydrocarbon mixture having exactly the desired motor fuel distillation range was effected and the heavier portion passed to tank 94 for later use as charging stock for another run. The fractionated vapors were condensed in condenser 106 and after separation of the uncon- 25 densable gas in element 104, the condensate was run to the storage tank 110. A portion of this condensate was returned to the top of the second column to control fractionation. The pressures in the various elements of the system were kept as 30 low as possible.

After the exhaustion of the fresh feed, the bottoms of the two fractionating columns 50 and 86 were used as charging stock. The operation was the same as in the case of fresh charging stock except that the pipe still outlet temperature was raised to about 895° F. and that of conversion chambers 28 and 30 to about 875° F. The heavier hydrocarbon fractions obtained from the bottom of the two fractionating columns when using this stock was then accumulated for use as second rerun stock. The operation using this last stock was the same as for the fresh charging stock with the exception that the pipe still outlet temperature was again raised to about 950° F. and that of the conversion chambers to about 925° F.

The ultimate yield of finished motor fuel with distillation range corresponding to U. S. motor fuel "V" from the fresh charging stock was above 75%. This motor fuel required no further treatment of any kind. Chemical and physical analyses and tests showed it to be of very high quality. Its high antiknock characteristics were indicated by its 90 octane number and its chemical stability was shown by the results obtained from several 55 oxidation tests. The oxidation induction period for this motor fuel was 25 hours when exposed to an atmosphere of oxygen at a pressure of 100 lbs. per sq. in. and at a temperature of 212° F. No residue was left after evaporation of 100 cc. in either a glass dish or a copper dish.

A fresh Pennsylvania gas oil charging stock with a distillation range of 400 to 700° F. and a gravity of 40° A. P. I. when processed in exactly the same manner as the Coastal gas oil gave approximately the same yield. The quality of the motor fuel of the same distillation range as that obtained from the Coastal gas oil was the same with the exception that the octane number was 85.

The examples given are not intended in any way to restrict the effective operation of the process and apparatus over other suitable ranges of temperature and pressure. A few of the more important values for pressure and temperature are as follows. The pipe still may operate at pres- 75

sures up to 1500 lbs. per sq. in. and at outlet temperatures of 800 to 1020° F. The catalytic conversion chambers may operate at pressures up to 1500 lbs. per sq. in. and temperatures of 780 to 1000° F. The refining catalytic chambers may operate at pressures up to 1500 lbs. per sq. in. and temperatures of 500 to 700° F. During regeneration, all of the catalytic chambers will be maintained within a temperature range where combustion of contaminants may be effected by admission of air but where the activity of the catalyst will not be destroyed or impaired. For supporting combustion it cannot drop much below 700° F., but its upper limit will depend largely upon the catalyst which is used. With hydrosilicate of alumina of the type disclosed in my aforesaid copending application Serial No. 600,581, which is the preferred catalyst, the temperature of regeneration should not be permitted to rise much above 1050° F. While the use of substantial pressure in the system may be desirable under certain conditions, it appears to reduce the anti-knock qualities of the product and for this reason in the production of a gasoline for present day high compression engines the pressure in the system should be kept as low as possible, especially in the catalytic chambers.

I claim as my invention:

1. The process of producing completely refined low boiling hydrocarbons of superior stability and antiknock rating from high boiling hydrocarbons in a continuous operation which comprises continuously vaporizing the high boiling hydrocarbons by raising their temperature above 800° F., transforming the resulting vapors at a temperature, not over 1000° F., by the action of a contact mass having suitable selective adsorptive or catalytic properties comprising activated hydrosilicate of alumina in molded form, cooling and fractionating the resulting vapors to separate out the desired low boiling products, raising the desired low boiling products to a temperature above 500° F. by heat exchange with the vapor products of said transforming step while cooling said last named products, and refining and stabilizing the said desired low boiling products at a temperature between 500 and 700° F. by the action of contact material having suitable selective adsorptive or catalytic properties comprising essentially activated hydrosilicate of alumina in molded pieces.

2. Process of manufacture of high-antiknock, low boiling hydrocarbons from high boiling hydrocarbons comprising vaporizing the high boiling hydrocarbons by heating them to 800-1020° F., contacting the vapors at a temperature of 800° to 1000° F. with either of two catalytic masses having selective adsorptive properties and comprising essentially activated hydrosilicate of alumina in molded pieces to effect a partial conversion, cooling the converted vapors, separating the latter into low boiling vapors and high boiling liquid, cooling the high boiling liquid, heating the low boiling vapors by heat exchange with said converted vapors, contacting the low boiling vapors at a temperature of 500 to 700° F. with either of two refining catalytic masses having selective adsorptive properties and comprising activated hydrosilicate of alumina mixed with metallic oxide in molded pieces, separating the resulting products into lower boiling vapors and higher boiling liquid, condensing the lower boiling vapors to secure a finished product and alternately regenerating the contact masses for each of said

catalytic operations in order that the process may be operated continuously.

3. Process of manufacture of high antiknock, low boiling hydrocarbons from high boiling hydrocarbons comprising vaporizing the high boiling hydrocarbons by heating them to approximately 850° F., contacting the vapors at approximately 835° F. with either of two catalytic masses having selective adsorptive properties and comprising essentially activated hydrosilicate of alumina in molded pieces to effect a partial conversion, cooling the converted vapors and effecting a separation into low boiling vapors and high boiling liquid, cooling the high boiling liquid, heating the low boiling vapors by heat exchange with said converted vapors during the cooling of the latter, contacting the said low boiling vapors at approximately 650° F. with either of two refining catalytic masses having selective adsorptive properties and comprising activated hydrosilicate of alumina mixed with metallic oxide in molded pieces, separating the resulting products into lower boiling vapors and higher boiling liquid, cooling the higher boiling liquid, condensing the lower boiling vapors to secure a finished product, maintaining continuous operation of the process by alternately regenerating the contact masses for each of said catalytic operations and effecting a partial heating of the high boiling hydrocarbon charge by heat exchange selectively with the said separated liquids before said first named vaporizing step.

4. Process of manufacture of high anti-knock stable low boiling hydrocarbons from high boiling hydrocarbons comprising vaporizing the high boiling hydrocarbons by heating them to a temperature above 800° F., separating entrained liquid from the resulting vapors, cooling the separated liquid, contacting the vapors at a temperature of 800 to 1000° F. with either of two catalytic masses having selective adsorptive properties and capable of effecting a partial conversion, cooling the converted vapors by heat exchange with the high boiling hydrocarbon charge, separating the converted vapors into low boiling vapors and high boiling liquid, cooling the high boiling liquid, contacting the low boiling vapors after heat exchange with said converted vapors at a temperature of 500 to 700° F. with either of two refining catalytic masses having selective adsorptive properties and comprising activated hydrosilicate of alumina and nickel oxide in molded pieces, separating the resulting products into lower boiling vapors and higher boiling liquid, cooling the higher boiling liquid, condensing the lower boiling vapors to secure a finished product, selectively heating said charge by heat exchange with the said separated liquids, and alternately regenerating the contact masses for each of said catalytic operations in order that the process may be operated continuously.

5. In the refining of low boiling hydrocarbons in the gasoline boiling range, the process steps of heating low boiling gasoline material substantially free of higher boiling material to a temperature above 500° F. and contacting the latter while in vapor phase and at a temperature within the range of 500° to 700° F. with a single catalytic mass having selective adsorptive properties and capable of refining and stabilizing said vapors, said mass being subject to poisoning by sulphurous material and comprising activated hydrosilicate of alumina mixed with metallic oxide from the class of oxides which are subject to poisoning by sulphurous materials, said mass being formed

in molded pieces capable of regeneration in place.

6. In the refining of low boiling hydrocarbons in the gasoline boiling range, the process steps of heating low boiling gasoline material substantially free of higher boiling material to a temperature above 500° F. and contacting the latter while in vapor phase and at a temperature within the range of 500 to 700° F. with a single catalytic mass having selective adsorptive properties and capable 10 of refining and stabilizing said vapors, said mass comprising activated hydrosilicate of alumina mixed with nickel oxide and formed in molded pieces capable of regeneration in place.
7. In the refining of low boiling hydrocarbons 15 in the gasoline boiling range, the process steps of heating low boiling starting material which is substantially free of higher boiling material to a temperature above 500° F. and contacting the vapors at about 650° F. with a single catalytic mass 20 having selective adsorptive properties for removing gum forming constituents and for refining and stabilizing said vapors, said mass made up of molded pieces formed of activated hydrosilicate of alumina containing nickel oxide and intended for 25 regeneration in place.

8. Apparatus for the catalytic conversion of higher boiling hydrocarbons into lower boiling hydrocarbons comprising a still, a plurality of catalyst chambers, means selectively to conduct vapors from said still to said chambers, a fractionating column, a heat exchanger connected to the outlet of said chambers and to the top of said column, means to conduct vapors from said chambers through said heat exchanger to the bottom 30 of said column, a plurality of refining catalyst chambers, means selectively to conduct vapors from said column through said heat exchanger to said refining chambers, a second fractionating column, condensing means for vapors issuing from 35 said second column, and means for effecting regeneration of the catalytic masses in all of said chambers whereby each chamber may be used alternately on stream and in regeneration for 40 continuous operation of the apparatus.

- 45 9. Apparatus for the catalytic conversion of higher boiling hydrocarbons into stable lower boiling hydrocarbons comprising a still, a plurality of catalyst chambers maintained at a temperature above 800° F., means selectively to conduct vapors from said still to said catalyst chambers, a fractionating column, a heat exchanger, means to conduct vapors from said chambers through said heat exchanger to the bottom of said column, a plurality of refining catalyst chambers 50 maintained at a temperature not over 700° F., means selectively to conduct vapors from said column through said heat exchanger to said refining catalyst chambers, a second fractionating column, a condenser for vapors from said second

5 column, discharge lines for liquid from both of said columns, means in said lines for cooling said liquids, means for selectively utilizing said last named means partially to heat the charge fed to said still, and means for effecting regeneration of the catalytic masses within all of said chambers in situ whereby continuous operation of said apparatus may be effected.

10. Apparatus for the catalytic conversion of higher boiling hydrocarbons into high antiknock 10 lower boiling hydrocarbons comprising a still, a separator for entrained liquid connected to said still, a plurality of catalyst chambers maintained at a temperature between 800 and 1000° F., means selectively to conduct vapors from said 15 separator to said catalyst chambers, a fractionating column, a heat exchanger, means to conduct vapors from said chambers through said heat exchanger to the bottoms of said column, a plurality of refining catalyst chambers maintained at a temperature between 500 and 700° F., means selectively to conduct vapors from the top 20 of said column through said heat exchanger to said refining catalyst chambers, a second fractionating column, a liquid discharge line from 25 said separator having a heat exchanger therein, a liquid discharge line from said first column having a heat exchanger therein, a liquid discharge line from said second column having a heat exchanger therein, means for selectively 30 conducting charge through said three last named heat exchangers to said still, means for selectively admitting a regenerating medium to each of said chambers, and means for conducting the fumes 35 of regeneration from each of said chambers.

- 40 11. Apparatus for the catalytic conversion of higher boiling hydrocarbons into stable low boiling hydrocarbons comprising a still, two catalyst chambers, means selectively to conduct vapors from said still to said catalyst chambers, a fractionating column, a heat exchanger, means to conduct vapors from said chambers through said heat exchanger to the bottom of said column, two refining catalyst chambers, means selectively to conduct vapors from the top of said column 45 through said heat exchanger to said refining catalyst chambers, a second fractionating column, condensing means for the vapors issuing from said second column, discharge lines for liquid from the bottom of both said columns, a heat 50 exchanger in each line, means for selectively conducting charge for said still through said last named heat exchangers, and means for effecting regeneration in situ of the catalytic masses in all said chambers whereby continuous operation of the apparatus may be effected, by having one of each pair of chambers in operation while the other is in regeneration.

EUGENE J. HOUDRY.
